COMBINED PORTABLE VACUUM CLEANER AND ACCESSORY CART

Philip S. Egan, Glenview, Ill., assignor to Sears, Roebuck and Co., Chicago, Ill., a corporation of New York

Application September 5, 1957, Serial No. 47,618

Term of patent 14 years

(Cl. D9—2)

Fig. 1 is a front perspective view of a combined portable vacuum cleaner and accessory cart embodying my new design, and

Fig. 2 is a rear elevational view of Fig. 1 shown on a smaller scale.

The side not shown in the drawing is substantially the same in appearance as the side shown and the bottom is plain.

The dominant features of my design reside in the portions shown in full lines.

I claim:

The ornamental design for a combined portable vacuum cleaner and accessory cart, as shown and described.
